DISPENSER CAP

Robert Podall, Chicago, Ill., assignor to Aerosol Research Company, a corporation of Illinois

Filed Aug. 20, 1964, Ser. No. 81,380

Term of patent 14 years

(Cl. D58—26)

FIGURE 1 is a perspective view of a dispenser cap embodying my new design;

FIG. 2 is a top plan view of the dispenser cap of FIGURE 1;

FIG. 3 is a front elevational view thereof;

FIG. 4 is a rear elevational view thereof; and

FIG. 5 is a side elevational view thereof.

The portions shown in broken lines are for illustrative purposes only.

I claim:

The ornamental design for a dispenser cap, substantially as shown and described.
